UNITED STATES PATENT OFFICE.

ERNST WILHELM GUSTAV CARL HOFFMANN, OF CHARLOTTENBURG, GERMANY, ASSIGNOR TO THE SIEMENS & HALSKE ELECTRIC COMPANY OF AMERICA, OF CHICAGO, ILLINOIS.

BRAKE.

SPECIFICATION forming part of Letters Patent No. 607,852, dated July 26, 1898.

Application filed December 29, 1897. Serial No. 664,389. (No model.)

To all whom it may concern:

Be it known that I, ERNST WILHELM GUSTAV CARL HOFFMANN, a subject of the Emperor of Germany, residing at Charlottenburg, Germany, have invented new and useful Improvements in Brakes, (Case No. 94,) of which the following is a specification, reference being had to the accompanying drawings, forming a part of this specification.

10 My invention relates to brake-shoes, and has for its object the provision of an improved brake shoe or block which may have a braking action through the agency of magnetism.

The invention, generally speaking, consists 15 in a magnetized body of metal, or metal that is adapted to be magnetized, suitably supported beneath the car-body, which through the agency of suitably-controlled means acts upon the wheel associated therewith to stop 20 or retard its rotation.

The preferred form of the invention consists in a brake-shoe provided with a magnetizing-helix of wire, which is energized when it is desired to have the brake act upon the 25 wheel. I preferably mount the brake-shoe so that it will not only have a magnetic braking action upon the wheel, but will also have frictional contact therewith.

A car or vehicle may be equipped with the 30 brake-shoe of this invention in a manner to permit of the mechanical operation of the brake, as heretofore, as well as the magnetic action, so that in the event of failure of current the brake may still be made to perform 35 its function.

The invention will be more readily understood by reference to the accompanying drawings, which illustrate the preferred embodiment thereof.

40 Figure 1 is a diagrammatic view showing an electromagnetic brake-shoe in position upon a car and a circuit for controlling the action thereof. Fig. 2 is a detail sectional view of the brake on line 2 2 of Fig. 3, a car-wheel also being shown in elevation. Fig. 3 is a sectional view on line 3 3 of Fig. 2, the car-wheel being removed. Fig. 4 is a sectional plan view on line 4 4 of Fig. 1, the car-wheel being shown in full plan.

Like letters indicate like parts throughout 50 the different views.

Referring more particularly to Fig. 1, the brake-shoe *a*, whose preferred construction will be more fully hereinafter set forth, is suspended by links *b* from the body of the car, 55 the lower ends of the links engaging trunnions *c*, projecting from the brake-shoe. The brake-shoes are normally slightly removed from the peripheries of the wheels. The coil *d* of the brake-shoe may have one of its terminals grounded through the wheels of the car and the other terminal connected with a suitably-graduated resistance *e*.

An electric car is illustrated provided with a trolley conducting mechanism engaging the 60 trolley-wire *f* to convey current to the car.

To apply the brake-shoe, current may be passed from the trolley conductor by means of the hand-switch *g* through the helix upon the shoe, which thereupon engages the periphery of the car-wheel. The brake may also be operated in other ways in addition to the 65 electrical operation, in which case the brake acts as a friction-brake if for any reason it is impossible to magnetize the brake-shoe. 70

Referring now more particularly to Figs. 2, 3, and 4, the preferred form of an electromagnetic brake will be particularly described. An oblong iron core *h* is provided with a flange *h'*, bolted at its periphery to a box-like 80 iron body *i*. A space intervenes between the core *h* and the iron body *i*, in which the energizing-helix *d* is disposed. The core *h* is provided with three polar projections *h²h²h²*, while the iron portion *i* is provided with four 85 polar projections *i' i' i' i'*. The poles *h² i'* are alternately disposed, a sufficient space being provided between the poles to prevent the magnetic flux from being shunted from the car-wheel. The faces of the poles opposed 90 to the car-wheel conform in curvature to the periphery of the wheel. The number of poles may be varied as desired.

When the helix is energized, polar regions of negative sign, for example, are formed at 95 *h²h²h²*, while polar regions of positive sign are formed at *i' i' i' i'*. When the parts are thus energized, the brake-shoe will be attract-

ed toward the wheel and have frictional engagement therewith, the force of this engagement depending upon the strength of the current. More or less circling magnetic lines of force are set up, according to the velocity of the periphery of the wheel, each point upon the periphery changing its polarity seven times in passing the brake-shoe. When the speed of the wheel is slackened, these currents may become weaker, but the rim will be more thoroughly magnetized. Consequently the magnetic attraction will be increased, so that the braking force, by properly proportioning the spaces between the poles, 15 may be made practically constant.

While the preferred embodiment of the invention is herein shown and particularly described, it is obvious that other embodiments of the invention may be made without departing from the spirit thereof. I have particularly omitted the enumeration and description of many modifications. The invention may be employed in other connections than that mentioned.

Having thus described the preferred embodiment of the invention, I claim as new and desire to secure by Letters Patent—

1. In a brake-shoe, the combination with the magnetic core h provided with a plurality 30 of poles h^2 , of a helix d surrounding said core, and an inclosing magnetic mass i united with the core h , a space intervening between the

core h and the mass i in which said helix is disposed, the mass i being provided with a plurality of polar projections i^1 , the polar 35 projections of the core being alternately disposed with relation to the polar projections of the mass i , the surfaces of the polar projections that are to be applied to the wheel practically conforming in contour to the periphery thereof, substantially as described.

2. In a brake-shoe, the combination with two masses of magnetic metal, each having a plurality of polar projections which are adapted to engage a wheel, of an energizing helix, the helix and magnetic masses being so disposed that when said helix is energized polar regions of one sign are formed at the polar projections of one mass and polar regions of an opposite sign are formed at the 50 polar projections of the other mass, the polar projections of one mass of magnetic material being alternately disposed with relation to the polar projections of the other mass of magnetic material, certain of the polar projections of each mass being interposed between polar projections of the other mass, substantially as described.

In testimony whereof I affix my signature in the presence of two witnesses.

ERNST WILHELM GUSTAV CARL HOFFMANN.
